SET OF PLAYING CARDS

Michael Tynio, 4816 Franklin St., Harrisburg, Pa.

Filed Feb. 7, 1961, Ser. No. 63,850

Term of patent 14 years

(Cl. D34—5)

FIGURES 1 through 8, inclusive, are top plan views of a set of playing cards showing my new design. The deck of playing cards comprises forty cards divided into five suits each of a different color, the remaining thirty-two not being shown.

The cards are of no appreciable thickness, and the backs thereof are conventional.

The dominant feature of each suit of the deck resides in the provision of the Spearman and Archer cards shown in FIGURES 6 and 7, aside and apart from the deck taken as a whole, the remaining illustrated cards being shown as broken away in order to illustrate the environ-

ment of the predominating design of the cards illustrated in FIGURES 6 and 7.

I claim:

The ornamental design for a set of playing cards, as shown and described.
